UNITED STATES PATENT OFFICE.

MEYER L. ROBBINS, OF NEW YORK, N. Y.

DESIGN FOR A SEWING-THIMBLE.

43,828.

Specification for Design.

Patented Apr. 8, 1913.

Application filed January 29, 1912. Serial No. 674,154. Term of patent 7 years.

To all whom it may concern:

Be it known that I, MEYER L. ROBBINS, a citizen of the United States, and a resident of New York, borough of Manhattan, in the county of New York and State of New York, have invented a certain new, original, and ornamental Design for Sewing-Thimbles, of which the following is a specification.

In the accompanying drawing, Figure 1

is a view in elevation of a thimble having my new design applied thereto. Fig. 2 is a bottom plan view thereof.

I claim:

The ornamental design for a sewing thimble, as shown.

MEYER L. ROBBINS.

Witnesses:

ARMAND MANTONE,
ALMA A. ROLLER.
